ARCH SUPPORT

Joseph C. Howell, Fort Lee, N. J.

Application April 3, 1935, Serial No. 14,430

12 Claims.

(Cl. 36—71)

This invention relates to arch supports and has particular reference to an adjustable support for the inner longitudinal arch of the foot.

The invention further comprehends an arch support including means connecting the same with the shoe to permit of longitudinal adjustment in the region of the inner longitudinal arch, angular adjustment about a point located under the inner longitudinal arch and vertical adjustment to various elevations above the sole of the shoe.

The invention more specifically comprehends, in an arch support of the indicated character, a flexible resilient arch plate having its highest point under the inner longitudinal arch, a tension plate underlying the arch plate and connected therewith for effecting upward arching of the arch plate, means anchored to the sole of the shoe and means of connection between the tension plate and anchoring means for adjusting the arch support longitudinally, transversely and angularly with reference to the sole of the shoe.

The invention also includes, in an arch support of the type specified, means for exerting a stress on the tension plate for effecting a differential upward arching of the arch plate to vary the height of the arch support.

More particularly the invention includes a flexible resilient longitudinally arched supporting plate having its highest point under the inner longitudinal arch and decreasing in elevation laterally towards the outer longitudinal arch with its ends located respectively adjacent the heel and ball portions and bearing upon the upper surface of the sole of the shoe.

The invention further includes a longitudinal arch supporting plate of the indicated character, a tension plate underlying the inner longitudinal arch and connected with the arch plate for effecting and maintaining an upward arching thereof and means anchored to the sole of the shoe under the inner longitudinal arch and connected to the tension plate for adjusting the arch support with reference to the sole of the shoe.

The invention further embodies means for effectively retaining the arch plate in selected adjusted position and which means also admits of further adjustment when necessary.

The invention also has in view an improved arch support which is simple in construction and operation, which is capable of economical production, and which is effective for its intended purpose.

With the above recited and other objects in view, reference is made to the following specifi-

cation and accompanying drawings in which there has been illustrated several embodiments of the invention, while the appended claims cover variations and modifications thereof which fall within the scope of the invention.

5

Fig. 15 is a longitudinal sectional view therethrough taken approximately on a plane indicated by the line 15—15 of Fig. 14.

45

Fig. 16 is a collective perspective view of the means for detachably and adjustably connecting the arch support to the shoe sole, the parts being shown in separated juxtaposition.

Referring to the drawings by characters of reference and more particularly to the form of the invention illustrated in Figs. 1 to 4 inclusive, A designates generally the arch support which includes a thin spring metal or equivalent longitudinal arch plate 10 which plate overlies a

55

portion of the heel of the shoe B, extends forwardly therefrom under the inner longitudinal arch to a point adjacent to and at one side of the metatarsal arch and laterally from the medial portion of the inner longitudinal arch to a point adjacent the outer longitudinal arch. The plate 10 has its highest point disposed under the inner longitudinal arch and decreases in height therefrom laterally towards the outer longitudinal arch with its forward end 11, rear end 12 and intermediate laterally projecting curved edge portion 13 bearing upon the upper surface of the sole of the shoe. In order to increase the flexibility of the curved edge portion 13, the plate 10 may be provided with radially disposed slits 14 extending inwardly from the marginal edge thereof. The inner side edge of the arch plate 10 may be formed with an upwardly curved extension or lip 15 which supports the side of the foot adjacent the inner longitudinal arch.

An auxiliary leaf or spring metal ply 16 underlies the extension 15 and extends inwardly under the body of the plate to reinforce the same under the inner longitudinal arch. The leaf or ply 16 is welded or otherwise secured medially thereof to the plate 10 and with its ends free or unsecured and terminating at points spaced from the ends 11 and 12 so that the same may flex or bend independently of the arch plate 10.

30 The arch support A also includes a tension plate 17 which underlies the arch plate 10 in the region of the inner longitudinal arch and which has its opposite ends welded or otherwise secured to the arch plate 10 adjacent the ends 11 and 12 thereof. The tension plate 17 is formed with a generally longitudinally extending slot 18 having longitudinally spaced laterally extending notches 19 and 20 in its opposite side edges disposed in transverse alignment.

40 For the purpose of detachably connecting the arch plate A to the sole of the shoe B, an anchoring device is employed which includes a threaded shank 22 depending from a flat head 23 which engages against the upper surface of the stress plate 17 with the shank 22 projecting downwardly through the slot 18. The head 23 is provided with one or more depending key pins 24 which extend through the slot 18 and are anchored in preformed key sockets 25 in the sole of the shoe. An internally threaded sleeve 26 is rotatably mounted in an opening 27 in the shoe sole and is designed to receive the threaded shank 22 which depends through an opening 28 in the upper surface of the shoe sole and communicating with the opening 27. The sleeve 26 is provided with a kerfed head 29 which is exposed at the bottom of the shoe for turning the sleeve so as to draw the shank 22 and the stress plate 17 downwardly against the upper surface of the shoe sole, the key pins 24 engaging the key sockets 25 so as to retain the shank 22 against turning movement.

Under this arrangement, the shank 22 may be loosened and the arch support A adjusted longitudinally, laterally or angularly with reference to the shank 22, the shank being selectively engaged in any one of the notches 19 or 20. After the arch support has been set, in the relative position desired, the sleeve 26 is tightened on the shank 22 so as to draw the stress plate 17 downwardly against the upper surface of the sole of the shoe thereby, securing the arch support in adjusted relation.

75 In the form of the invention illustrated in Figs.

5 to 7 inclusive, the arch support designated generally by the reference character C includes a longitudinally arched sheet metal or equivalent flexible resilient stress plate 30 which has its highest point under the inner longitudinal arch and which decreases in elevation laterally towards the outer longitudinal arch. The stress plate is supported at its forward end 31 upon the inner surface of the sole of the shoe D in the region adjacent one side of the metatarsal arch and its rear terminal 32 is supported by and upon the heel portion of the shoe D while the intermediate laterally projecting curved edge portion 33 rests upon and is supported by the shank portion of the shoe. The laterally extending curved edge portion 33 is preferably provided with radially disposed slits 34 extending inwardly from the marginal edge thereof so as to increase the flexibility of this portion of the stress plate.

The arch support C also includes a longitudinally arched sheet metal or equivalent flexible resilient arch supporting plate 35 which overlies the stress plate 30 and has its highest elevation adjacent the side edge under the inner longitudinal arch. The said plate 35 decreases in height laterally to the curved side edge 36 where it merges with the upper surface of the stress plate 30 and is welded or otherwise secured thereto adjacent the said curved edge and at the ends 37 and 38 which overlie the ends 31 and 32 respectively of the plate 30. The arch supporting plate 35 is preferably provided with an upwardly curved extension or lip 39 which supports the side of the foot adjacent the inner longitudinal arch.

30 The arch support C is detachably connected to the sole of the shoe D by an anchoring device similar in construction to the anchoring device illustrated in Figs. 1 to 4 inclusive, and which includes a threaded shank 40 depending from a flat head 41 which head overlies the upper surface of the stress plate 30 beneath the arch supporting plate 35 with the shank 40 projecting downwardly through a generally longitudinally disposed slot 42 in the stress plate 30 which slot is provided with longitudinally spaced laterally extending notches 43 disposed in transverse alignment in the opposite side edges thereof.

40 The anchoring device also includes an internally threaded sleeve 53 which is rotatably mounted in an opening formed in the sole of the shoe D and is designed to receive the threaded shank 40. The sleeve 53 is provided with a kerfed head which is exposed at the bottom of the shoe for turning the sleeve so as to draw the shank 40 and the stress plate 30 downwardly to secure the arch support in position. The head 41 is provided with one or more depending keys 54 which extend through the slot 42 in the stress plate and engage in preformed key sockets in the upper surface of the sole of the shoe when the stress plate is drawn downwardly by the tightening of the sleeve 53 on the shank 40.

50 If desired, a metatarsal arch support 44 may be used in conjunction with the arch support C, the metatarsal arch support 44 including a base 45, of generally oval formation, constructed of leather, rubber or any analogous flexible material. The base 45 is provided at the rear adjacent one side thereof with longitudinally spaced laterally disposed slots 46 which are designed to underlie the slot 42 in the stress plate and align with the notches 43 thereof. The arch support 44 also includes a pad element 47 which

5

is of lesser area than the base 45 and has its marginal edge spaced from the marginal edge of the base and which pad is formed with a flat lower surface and a convex upper surface, the highest point thereof being substantially centrally under the metatarsal arch and inclining towards the marginal edge thereof. The pad element 47 is cemented or otherwise secured upon the upper surface of the base 45 and may be constructed of rubber, felt or any equivalent yieldable elastic cushion material.

The arch support 44 is adjustably connected with the arch support C by means of the stud 40 engaging through any one of the slots 46 in the base 45, the upper surface of the base 45 being disposed against the lower surface of the stress plate 30 with the unsecured rear portion 48 of the pad element 47 extending over the upper surface of the forward portion of the stress plate 30 and the arch supporting plate 35. When the metatarsal arch support 44 is employed in conjunction with the arch support C, a rigid washer 49, preferably of metal, is applied against the underside of the base 45, the washer being provided with a central opening 50 for receiving the shank 40 and eccentric openings 51 through which the key pins 54 project. A lock nut 52 is threadedly engaged on the shank 40 for tightening the washer to clamp the base 45 against the undersurface of the tension plate 30.

In the form of the invention disclosed in Figs. 8 and 9 of the drawings, the arch plate E, which is of the same general shape as that disclosed in the previous forms, is provided with an extension 55 extending forwardly from its rear end and provided with a longitudinal slot 56 having communicating longitudinally spaced notches 57 in its opposite side edges. The arch plate E is also provided with a tension strap 58 connected to the forward end thereof and extending rearwardly therefrom, said tension strap being formed at its rear portion with a longitudinal slot 59 which registers with and underlies the slotted and notched portions 56 and 57 of the extension 55. The rear end of the tension strap has journaled therein on lateral trunnions 60 a nut 61 which is threadedly engaged by an adjusting screw 62 extending rearwardly through the heel portion of the shoe with a kerfed head 63 at its rear end countersunk in the rear of the heel and exposed for the purpose of turning said screw. An anchoring element including a flat head 64 with a depending threaded shank 65 is engaged through the slot 56 of the extension 55 and through a washer 65a lying within the slot 59 of the tension strap 58, with a nut 65B engaged over the shank 65 and adapted to clamp the extension 55 to the anchoring element. The lower end of the shank 65 extends through an opening 66 in the sole of the shoe where it is engaged by a threaded sleeve 67 rotatably mounted in an opening in the shoe sole with a countersunk kerfed head 68 for turning the sleeve. The anchoring element is also provided with depending key pins 69 extending through openings in the washer 65a and adapted to enter pre-formed key sockets provided in the upper surface of the sole of the shoe to hold the shank 65 against rotation.

In use, after the shank 65 and extension 55 of the arch plate E have been adjusted relative to each other to locate the arch support in the desired longitudinal position in the shoe, the nut 65B is tightened to retain the adjustment of these

parts. The shank 65 is then inserted in the threaded sleeve 67 and the set screw 62 is then turned to adjust the arch plate to vary the curvature of the arch plate E so as to obtain the desired elevation. After this adjustment is made, the sleeve 67 is turned to draw the shank 65 downwardly and thereby lock the arch plate in the elevation set.

In the form of the invention shown in Fig. 10 of the drawings, the arch plate F is of similar construction and is provided with forwardly and rearwardly extending tension straps 70 and 71 each of which is provided at its free end with a nut 72 journaled by means of laterally projecting trunnions 73 on a horizontal axis. A turn buckle 74 having oppositely projecting oppositely threaded shanks 75 engaging the nuts 72 is provided for the purpose of adjusting the tension on the arch plate to vary the elevation of the arch plate. The forwardly extending tension strap 70 is formed with a longitudinal slot 76 having longitudinally spaced laterally projecting notches 77 adapted to cooperate with an anchoring device of the type set forth in Figs. 8 and 9 for adjustably anchoring the arch plate to the shoe.

In the form of the invention shown in Figs. 11, 12 and 13, the arch support includes an upper ply of leather 80 which extends from a point medially of the heel of the shoe to a point at the ball of the shoe and following generally the contour of the last of the shoe in this region. A lower ply of leather 81 is connected by stitching 82 to the cover ply 80 and provides therebetween a pocket for the reception of a yieldable elastic pad 83 which is inserted therein at the unstitched portions of the ply lying at the inner side of the shoe. Between the top of the sole of the shoe G and the lower ply of leather 81, a metallic unit composed of a plurality of spring leaves 84, 85 and 86 is arranged, the leaves and the lower leather ply 81 being provided with aligned longitudinally extending slots 87 having longitudinally spaced notches at the opposite longitudinal edges thereof. The spring leaves are provided with upturned lips or extensions 88 lying alongside of the pad 83 and covered by an extension 90 of the cover ply 80. The arch support is attached to the shoe by an anchoring device including a flat head 91 overlying the lower leather ply 81 and having a threaded shank 92 extending downwardly through the aligned slots 87. The head 91 of the anchoring device is also provided with depending key pins 94 and a washer 95, apertured to receive the shank 92 and the key pins, is fitted thereover and the assemblage locked in place by a lock nut 96. The threaded shank extends downwardly through an opening in the shoe and is engaged by an interiorly threaded sleeve 97 having a kerfed head 98 rotatably mounted in an opening in the sole of the shoe for locking the arch support in position while permitting of longitudinal adjustment thereof.

In the form of the invention disclosed in Figs. 14 to 16 inclusive, the arch support which is designated generally by the reference character H includes an arch plate 100 for supporting the inner longitudinal arch and which conforms substantially to that of the previous forms. The arch support also includes a tension plate 101 which is permanently attached at its forward and rear ends 102 and 103 to the underside of the forward and rear ends of the arch plate. In this instance, the tension plate 101 is formed with a longitudinally extending slot 104 and has a series of notches 105 communicating with the marginal edge of

the plate which forms the slot 104, the notches along the longitudinal edges being staggered with reference to each other.

The device for detachably and adjustably connecting the arch support H with the sole of the shoe I includes a tubular interiorly threaded stud 106 which is provided with an enlarged head 107 at its upper end, exterior threads 108 immediately below the head and longitudinal external splines 109 extending downwardly from the threaded portion 108 of the stud to the lower end thereof. The head 107 is located over the tension plate 101 with the stud 106 protruding downwardly through the slot 104. The disc-like lock nut 110 is threadedly engaged over the threaded portion 108 of the stud 106 and cooperates with the head 107 to clamp the tension plate in adjusted set position with reference to the stud 106, it being apparent that the arch member H may be set at longitudinally or angularly adjusted relations to the stud after which the lock nut serves to retain the adjustment. The detachable and adjustable means of connection between the arch support H and the sole of the shoe I further includes an anchoring member which consists of a tubular bushing 111 having a flange 112 at its upper end and formed with internal longitudinally extending splines 113 with which the external splines 109 of the stud 106 are adapted to engage to permit of the setting of the stud therein at various angular positions and to permit of relative vertical movement between the stud and the bushing for preventing rotation of said parts with reference to each other. The bushing is arranged in an opening formed in the sole of the shoe I with the flange 112 countersunk in the upper surface of the sole. Vertical adjustment of the stud 106 in the bushing is effected by means of a screw 114 which cooperates with internal threads of the stud, the screw being formed at its lower end with a flange 115 which is located between the lower end of the bushing 111 and a bottom plate 116 which is countersunk in the lower surface of the sole of the shoe I. The screw is provided with a kerfed head 117 which is exposed through a central opening in the bottom plate whereby the screw is swivelly mounted and is adapted to be turned from the outside of the shoe by means of an implement engaged with its kerfed head. The screw, in addition to serving as a means for connecting the stud and arch support H in place, is employed for the purpose of adjusting the elevation and curvature of the arch plate 101. In order to lock the screw 114 in vertically adjusted position, a lock screw 118 is adapted for selective threaded engagement in the threaded openings 119 formed in the flange 115.

In this form of the invention, one or more spring leaves 120 is arranged upon the upper surface of the sole of the shoe I with the apertured central portion overlying the flange 112 of the bushing. Rivets 121 extend through the sole of the shoe, through the bottom plate 116, the flange 112 and the spring leaves 120, to attach these parts together in assembled relation with the shoe sole. The spring leaves function to reenforce the arch of the shoe in the region of the arch support H.

What is claimed is:

1. An arch support for shoes including a longitudinally arched plate adapted to be arranged with its highest point under the inner longitudinal arch of the foot, said plate decreasing in height laterally towards the outer longitudinal arch of the foot with its ends adapted to be located adjacent the heel and ball portions there-

of respectively and with its lateral edge portion adjacent the outer longitudinal arch and its ends adapted to be supported by the upper surface of the sole of the shoe, a tension plate underlying the arched plate and connected thereto adjacent its ends, means adapted to be anchored to the sole of the shoe, and means of connection between the anchoring means and the tension plate for adjusting the arch support with reference to the sole of the shoe. 10

2. An arch support for shoes including a longitudinally arched plate adapted to be arranged with its highest point under the inner longitudinal arch of the foot, said plate decreasing in height laterally towards the outer longitudinal arch of the foot with its ends adapted to be located adjacent the heel and ball portions thereof respectively and with its lateral edge portion adjacent the outer longitudinal arch and its ends adapted to be supported upon the upper surface of the sole of the shoe, a plate underlying and connected to the arched plate and having a longitudinally extending slot therein, means adapted to be anchored to the sole of the shoe, and means of connection between the said anchoring means and said last named plate extending through the said slot for adjusting the arch support with reference to the sole of the shoe. 20

3. An arch support for shoes including a longitudinally arched plate adapted to be arranged with its highest point under the inner longitudinal arch of the foot, said plate decreasing in height laterally towards the outer longitudinal arch of the foot with its ends adapted to be located adjacent the heel and ball portions thereof respectively and with its lateral edge portion adjacent the outer longitudinal arch and its ends adapted to be supported upon the upper surface of the sole of the shoe, a plate underlying and connected to the arched plate and having a longitudinally extending slot therein, anchoring means adapted to extend through the sole of the shoe, and means of connection between said anchoring means and the last named plate extending through the slot therein for adjusting the arch support with reference to the sole of the shoe, said anchoring means including a screw rotatable from the exterior of the shoe for drawing the last named plate tightly against the inner surface of the sole of the shoe. 40

4. An arch support for shoes including a longitudinally arched plate, a plate underlying and connected to the arched plate and having a longitudinally extending slot therein, means adapted to be anchored to the sole of the shoe, and means of connection between the said anchoring means and said last named plate extending through the said slot for adjusting the arch support longitudinally and rotatably with reference to the sole of the shoe. 55

5. An arch support for shoes including a longitudinally arched plate, a plate underlying and connected to the arched plate and having a longitudinally extending slot therein, anchoring means adapted to extend through the sole of the shoe, and means of connection between said anchoring means and the last named plate extending through the slot therein for adjusting the arch support longitudinally and rotatably with reference to the sole of the shoe, said anchoring means including a screw rotatable from the exterior of the shoe for drawing the last named plate tightly against the inner surface of the sole of the shoe. 65

6. An arch support for shoes including a flex- 75

ible resilient longitudinally arched member, a flexible resilient plate underlying and secured to said arched member, said plate having a longitudinally extending slot therein, anchoring means 5 adapted to extend through the sole of the shoe, and means of connection between said anchoring means and said plate extending through the slot therein for adjusting the arch support longitudinally and rotatably with reference to the 10 sole of the shoe, said anchoring means including a screw rotatable from the exterior of the shoe for drawing the same downward into locking engagement with the sole of the shoe.

7. An arch support for shoes including a longitudinally arched plate adapted to be arranged with its highest point under the inner longitudinal arch of the foot, said plate decreasing in height laterally towards the outer longitudinal arch of the foot with its ends adapted to be located adjacent the heel and ball portions thereof respectively and with its lateral edge portion adjacent the outer longitudinal arch and its ends adapted to be supported by the upper surface of the sole of the shoe, a tension plate underlying 25 the arched plate and connected thereto adjacent its ends, means for varying the tension on said tension plate for producing a differential upward arching of the arch plate, means adapted to be anchored to the sole of the shoe, and means of 30 connection between the anchoring means and the tension plate for adjusting the arch support with reference to the sole of the shoe.

8. An arch support for shoes including a longitudinally arched plate adapted to be arranged 35 with its highest point under the inner longitudinal arch of the foot, said plate decreasing in height laterally towards the outer longitudinal arch of the foot with its ends adapted to be located adjacent the heel and ball portions thereof 40 respectively and with its lateral edge portion adjacent the outer longitudinal arch and its ends adapted to be supported by the upper surface of the sole of the shoe, a resilient arch supporting plate having its highest point under the inner 45 longitudinal arch and decreasing in height laterally towards the outer longitudinal arch, said arch supporting member being mounted upon and secured at its ends and along one side edge to the longitudinally arched plate, said longitudinally 50 arched plate having a longitudinally extending slot therein, means adapted to be anchored to the sole of the shoe, and means of connection between the said anchoring means and said longitudinally arched plate extending through the 55 slot therein for adjusting the arch support longitudinally with reference to the sole of the shoe.

9. An arch support for shoes including a longitudinally arched plate adapted to be arranged with its highest point under the inner longitudinal arch of the foot, said plate decreasing in height laterally towards the outer longitudinal arch of the foot with its ends adapted to be located adjacent the heel and ball portions thereof respectively and with its lateral edge portion adjacent the outer longitudinal arch and its ends adapted to be supported upon the upper surface 65 of the sole of the shoe, rearwardly and forwardly extending plates secured in overlapping relation

to the opposite ends respectively of the longitudinally arched plate, said last mentioned plates having longitudinally extending registering slots therein, an anchoring device adapted to be fixedly secured to the sole of the shoe, means of connection between the anchoring device and said last named plates extending through the said slots therein for mounting the arch support for relative adjustment with reference to the sole of the shoe, and means connected to the rearwardly 10 extending plate for varying the curvature of the longitudinally arched plate.

10. An arch support for shoes including a resilient arch supporting member, a flexible sheath having upper and lower plies secured together 15 throughout the major portion of the margin of one of the plies, the remaining unsecured portion defining a mouth for the insertion and removal of the resilient arch supporting member, an anchoring device therefor adapted to be 20 fixedly secured to the shoe sole, means of connection between the sheath and the anchoring device for mounting the same and the arch supporting member for relative longitudinal, lateral and rotatable adjustments with reference to the 25 shoe sole, and a resilient metallic plate underlying the sheath and including a plurality of plies connected with the anchoring device for corresponding relative longitudinal, lateral and rotatable adjustments with reference to the sole of the 30 shoe.

11. An arch support for shoes including a longitudinally arched plate, rearwardly and forwardly extending plates secured in overlapping relation to the opposite ends respectively of the longitudinally arched plate, said last mentioned plates having longitudinally extending registering slots therein, means adapted to be anchored to the sole of the shoe, means of connection between the said means and said last named plates 35 extending through the slots therein for mounting the arch support for relative adjustment with reference to the sole of the shoe, and means engaging said means of connection for locking the forwardly and rearwardly extending plates in 40 relative adjusted position for varying the curvature of the arch plate.

12. An arch support for shoes including a flexible resilient member for supporting the inner longitudinal arch, a flexible resilient plate underlying and supporting said arch member, said plate having a longitudinally extending slot therein, a metatarsal arch support including a flexible resilient pad and a flexible base therefor having a rearwardly extending portion formed 50 with a longitudinal series of openings, means adapted to be anchored to the sole of the shoe, and a common means for connecting the base of the metatarsal arch support to the underlying plate of the longitudinal arch support, extending through the slot therein and through the apertures of the base of the metatarsal arch support to permit of relative adjustment of the longitudinal arch support and the metatarsal arch support with reference to each other and with 55 reference to the sole of the shoe.

JOSEPH C. HOWELL.
